Collamer & Co.

UNITED STATES PATENT OFFICE.

JAMES A. TAYLOR, OF LIMA, INDIANA.

ROAD-SCRAPER AND CARRIER.

SPECIFICATION forming part of Letters Patent No. 570,885, dated November 3, 1896.

Application filed March 5, 1896. Serial No. 581,997. (No model.)

To all whom it may concern:

Be it known that I, JAMES A. TAYLOR, a citizen of the United States, and a resident of Lima, La Grange county, State of Indiana, have invented certain new and useful Improvements in Road-Scrapers and Carriers, (Case C;) and my preferred manner of carrying out the invention is set forth in the following full, clear, and exact description, terminating with claims particularly specifying the novelty.

This invention relates to road-scrapers and carriers, and more especially to that class thereof known as "self-loading carts;" and the object of the same is to produce improvements in the details of construction of devices of this character.

To this end the invention consists in a road-scaper constructed substantially as hereinabove described and claimed and as shown in the accompanying drawings.

Reference is made to United States Patents No. 552,936, dated January 14, 1896, and No. 555,270, dated February 25, 1896. In these 25 patents are shown details of construction somewhat similar to those set forth below, but no claim is made in the present case to anything covered by the claims in the patents hitherto issued.

Referring to the accompanying drawings, Figure 1 is an elevation taken from the left side of the machine complete, showing the same as carrying three scoops or scrapers, the forward one of which (lettered S) is illustrated in the act of scraping or taking up earth, the second one of which (lettered C) is shown as at a carry, and the rearmost one of which (lettered D) is illustrated as in a dumped position. (The remaining views omit 35 the arch carrying the seat, as well as the front wheels.) Fig. 2 is a similar view and with the parts in the same positions, but taken from the left side of the machine at a point just inside the left side bar of the framework, and thus showing certain parts in section. Fig. 3 is a plan view of the machine shown as going in the opposite direction and with the parts of the three scrapers in the same 40 positions. Fig. 4 is a longitudinal section on the line 4-4 of Fig. 3, looking from the right toward the inner face of the left side bar, the parts being in relatively the same positions

as in the views above. Fig. 5 is a cross-section of the scraper C, taken on the line 5-5 of Fig. 3. Fig. 6 is a perspective detail of a modified form of the arch. Fig. 7 is a perspective detail showing a modified form of the rear locking device. Fig. 8 is a plan view of the front axle and hounds. Fig. 9 is a perspective detail showing one of the blocks and its pivoted catch, which forms the bearing for the stub-shaft on the scoop.

In the said drawings the main framework comprises right and left longitudinal side bars R and L, suitably connected at proper intervals and supported by the rear axle A, carrying main wheels at its extremities, and having at their front ends arches a, upon which is mounted the driver's seat d.

F is the front axle, carrying at its extremities the forward main wheels and connected at its center by a king-bolt and fifth-wheel f with similar parts at the forward ends of the arches a, as will be understood.

H are hounds attached to the front axle, 75 and T is the tongue, preferably bolted, as at t, to the forward end of the hounds and connected with them at its rear extremity by transverse braces h. All these details, however, are only the preferred manner of building the framework, and it will be obvious that any other suitable framework may be substituted for that shown and described.

The machine herein illustrated has three 80 scoops or scrapers mounted between the side bars of the framework, and it is my intention to so construct it; but it will be obvious that each machine could carry a greater or less number of scrapers, according to the amount of work to be done, the roughness of the earth 85 at the point being treated, the strength of the team, and other conditions. Although I have not shown it, there is preferably a narrow platform extending along one or both sides of the framework and on which stands the operator who is to manipulate the levers described below, while the driver's sole duty is to control the team, drive to the proper points and at proper times, and stop the machine when it is desired to dump.

I might here add that the parts described below are of any desired sizes, proportions, and materials, and the exact shape of the parts is immaterial, except that they should

conform with the constructions recited in the claims, as will be understood.

In all cases the letter S designates a scoop or scraper (or the parts thereof) which is 5 scraping or in the act of taking up earth. C is one that is at "carry," by which I mean that when in this position the earth so taken up can be transported bodily by the machine, and D one that is dumped and held dumped 10 or in the act of being dumped, so as to discharge the contents of the scoop at the dumping-point.

Secured to and rising from the side bars of the frame are blocks 1, which have cut in 15 their upper ends transverse notches 2, which form bearings, and these blocks are also longitudinally notched, as at 3. In said notch 3, at one side of the bearing 2, is pivoted on a transverse pin 4 a catch 5, adapted to swing 20 down into the notch 3 and close the upper end of the bearing 2, the free end of this catch being held in place by a pin or other removable device 6.

7 is a strong arch (a modification of which 25 is shown in Fig. 6) whose center stands normally across and above the scoop and whose ends 8 turn downward and are provided with outwardly-projecting stub-shafts 9, which are journaled in said bearings 2. This arch may 30 be made in one or more pieces, as desired, and its center may be bowed slightly upward, as shown in Fig. 3 at S, or it may be straight, as seen in Fig. 6.

10 is the main lever, secured rigidly, as by 35 bolts, across one end of the arch. In the drawings it is shown at the left end when viewed from above, as in Fig. 3, although it will be obvious that it could be placed at the right end and all the levers be on this side of the machine. This lever is held firmly to the arch by a brace 11, attached to the lever and extending from its body obliquely across the arch, bowed slightly upward, and rigidly connected with a slotted arm 12, which projects 40 forward from the other end of the arch the same as does the forward end of the lever 10, which latter is also slotted. Pivoted in the front end of each slotted arm is a link 13, whose body moves through a guide, hereinafter described, and whose lower end is pivoted to the side of the scoop 14. Hence when 45 the handle of the lever is drawn to the rear the scoop is raised from the scraping position S to the carry position C, and during such movement the upright portions 8 of the arch pass over the supporting-pivots 9, by which it will be seen that the weight of the scoop can be very easily raised, and after being 50 raised is firmly held in the bearings.

60 15 are tongues projecting to the rear and downward from the rear end of the right slotted arm 12 and from the lever 10, the tips of these tongues engaging sockets 16 in the sides of the scoop when the latter is at carry.

65 17 are other tongues, which may be fastened to and project upward from the sides of the scoop and which are adapted to engage

70 sockets 18 in the right tongue 15 and in the lever 10 when the scoop is at carry. These tongues and sockets will firmly prevent lateral or longitudinal movements of the scoop both while at carry and while being dumped or after having been dumped, because in the act of dumping the scoop does not change its position with relation to the arch and lever. 75

20 is a curved and preferably metallic sheet located just forward of each scoop when the latter is in its carrying position and preferably having its extremities 20' bent to the rear, the function of this sheet being to guard 80 and prevent the exit of the dirt from the scoop at this time. This sheet is supported by rods 21, which may have slotted ends 22, connected adjustably by bolts 23 with the side bars of the frame, or which may have 85 their ends held by such bolts adjustably beneath clips 25, carried by said side bars. There is one guard for each scoop, as will be clear.

Projecting inward from the lower ends of 90 the upright portions 8 of each arch are pins 30, which engage slots 31 in the forward ends of a U-shaped bail 32, whose side bars are pivoted, as at 33, within the framework and whose rear member 34 stands across in rear 95 of the scoop and has rising therefrom two guide-fingers 35.

36 are hooks projecting rearward and downward from the upper rear corners of the scoop and adapted to pass over this bail just inside 100 said guide-fingers, and 37 are lugs located just beneath these hooks and in position to pass under the transverse portion of this bail when the scoop is in its scraping position. In the act of dumping the scoop and when it 105 is turned around the pivots 9 these hooks 36 rise off the bail 34 and the lugs 37 pass by such bail, while at carry the hooks rest upon the bail and support the rear end of the scoop, and in moving the scoop to a scraping position (as described below) it slides bodily to the rear, so that the lugs 37 pass under the bail and prevent the rear end of the scoop 110 from accidentally rising or being thrust farther rearward, while at this time the pins 30 115 raise the slotted front ends 32 of the bail and cause the rear side 34 of the latter to descend slightly, as will be seen in the drawings at S in Fig. 2. A slight modification of this construction is shown in Fig. 7, wherein the guide-fingers, hooks, and lugs are dispensed with, and in their place is substituted the following construction: The rear portion 34 of the bail carries adjacent each rear corner of the scoop an upright finger 35', and the corner of 120 the scoop has a horizontal loop 37' projecting to the rear and a hook 36' beneath it. This view shows in full lines the scoop in a scraping position, at which time the bail is drawn tightly into the hook 36' and the finger 35' 125 projects obliquely through the loop 37', so as to prevent the rear end of the scoop from rising. In dotted lines the parts are shown with the scoop at a carry, at which time the bail 130

has passed out of the hook 36' and the finger 35' rises straight upward through the loop 37', from which it may be bodily raised in the act of dumping.

5 The numeral 40 designates a long hook projecting forward from the rear of the scoop at its center, and this hook engages a catch 41, carried at the center of the arch 7.

42 is a thumb-lever carried by the main lever, and 43 is a rod for swinging the tip of this hook out of said catch. If the hook engages the right side of the catch, as seen in Fig. 3 at C, the rod 43 operates a pivoted pawl 44, so that pressure on the thumb-lever 42 will move the tip of the hook to the right; but if the hook engages the left side of the catch the construction will be as shown in Fig. 6, wherein the inner end of the rod 43 has a slot 46 sliding over a pin on the catch 40 and has a lip 47 at its free end so located as to disengage the hook from the left side of the catch. It will be clear that either construction may be employed without departing from the general principle. When the 25 scoop is raised from a scraping position to a carry, the catch moves backward until it engages the hook 40. This holds the scoop from falling, and when the same is dumped by the main lever the catch, by engaging the hook, causes the rear end of the scoop to be raised bodily around the pivots 9. When the scoop has been moved to its completely-dumped position, a hook 48, carried by the side bar of the frame, engages the main lever 10 to prevent a return movement of the scoop, and this hook is disengaged from the lever when it is desired to throw the scoop back to a carry.

At each side of the scoop or scraper 14, near the front end thereof, is secured a hook 50, 40 and connected therewith is a strap 51, extending longitudinally of and slightly remote from the scraper, so as to form a guide for the link 13, as above mentioned. Said hook is adapted to engage with another hook 52, 45 (best seen in Fig. 4 at S,) whose body is L-shaped and is pivoted at its angle at 53 to the side bar of the frame, its upright bar being pivoted to a slide 54, which is adapted to move longitudinally through the slot 3 in the block 1. This slide has a pin 55, engaged by a cam 56, which is secured to the upright portion of the end 8 of the arch 7, the construction being such that when the scoop is moved from a scraping position to a carry the cam 55 pushes on the pin and shoves the slide forward, whereby the upright arm of the hook 52 is pushed forward and the hook itself is caused to rise, this movement lifting the hook 50 and assisting in the elevation of the mouth 60 of the scoop. When the latter is turned on its pivots 9 for the purpose of dumping, the hooks 50 and 52 do not engage each other.

57 is a spring carried by the side bar of the framework and pressing the hook and slide in proper direction, so that when the scoop is moved from a carry to the scraping position the spring pushes the slide back with its pin

55 in contact with the cam and permits the proper movement of the hook 52 to engage it with the hook 50 on the scoop. The latter on reaching its lowermost position, ready for taking up earth, is therefore held by the engagement of the hooks with each other. A slight modification of this construction is shown in Fig. 2 at D, wherein the hook 52, 70 although pivoted at 53', is not of L shape, but has an arm 53" connected with the slide 54 in about the manner shown, the operation of this construction being practically the same as above described. 75

80 A team is hitched to the tongue, the driver takes his seat, and the machine is driven to the point where it is desired to take up earth. One or more of the scrapers are then lowered to the scraping position and the machine driven forward, so that loose earth from the surface of the ground will be taken into the several scoops, which may be thus lowered. When each scoop or scraper is filled, the attendant moves the lever 10 backward and the scraper is drawn to a carrying position where-in the guard will prevent the earth from running out of the scoop. All of the scoops having been filled, the machine is driven to the dump, and when it has arrived at the proper point 90 the assistant raises the main levers 10 to dump the scoops, as will be clear. The hooks 48 hold the scoops in dumped position, after which the machine is driven back to the place where the scraping is to be done, and the entire operation is repeated. This is done by disengaging the hook 48 from each lever and throwing the latter to the rear, so as to bring the empty scraper again to a carry. Then the thumb-lever 42 is manipulated to disengage the long hook 40 from the catch at the center of the arch, and by raising the lever the scoop is permitted to pass downward and slightly backward to pass the lugs under the bail, and finally engages the front hooks with each other just as its mouth reaches the proper position for scraping. 100

105 What is claimed as new is—

110 1. In a road-scraper, the combination with a framework, blocks carried by the side bars thereof and having transverse notches in their upper ends forming bearings and also provided with longitudinal notches in their upper ends, a catch pivoted at one extremity 115 in the latter notch at one side of the bearing and having its body passing across the bearing, and a pin holding the tip of the catch removably in place; of an arch having stub-shafts journaled in said bearings, a lever connected with said arch, a scoop also connected 120 with the arch, and means for holding the scoop in any one of several positions, as and for the purpose set forth. 125

130 2. In a road-scraper, the combination with a framework having bearings, an arch extending across the framework and having upright portions at its extremities, stub-shafts carried by said upright portions and journaled in the bearings, and a lever rigidly se-

cured across one end of the arch longitudinally of the machine; of an arm projecting forward from the opposite end of the arch, a scoop beneath the latter, links connecting the 5 front end of the scoop with said arm and with the front end of the lever, a brace extending from the rear portion of the lever obliquely across the arch and secured to the opposite arm, and detachable connections substantially as described between the center of the arch and the rear of the scoop, as and for the purpose set forth.

3. In a road-scraper, the combination with a framework, a transverse arch pivotally mounted thereon, a lever secured across one end of the arch longitudinally of the machine, an arm projecting forward from the other end of the arch, a scoop below the latter, links connecting the front ends of the arm and lever with the scoop, and detachable connections between the rear end of the scoop and the center of the arch; of tongues projecting to the rear and downward from said arm and from the lever, sockets in the sides of the scoop

25 for engaging these tongues, other tongues projecting upward from the sides of the scoop, and sockets in the first tongue and in the main lever for receiving these tongues, as and for the purpose set forth.

30 4. In a road-scraper, the combination with a framework, an arch pivotally mounted thereon, a lever projecting to the rear from said arch, a scoop below the latter, and pivotal connections between the arch and forward

35 end of the scoop; of a long hook projecting forward from the rear of the scoop, a catch carried by the center of the arch and with one side of which said hook engages, a thumb-lever on the main lever, and a rod connected 40 at one end to the thumb-lever and having its other end standing opposite the free end of the catch, as and for the purpose set forth.

5. In a road-scraper, the combination with a framework, an arch pivotally mounted 45 thereon, a lever projecting to the rear from said arch, a scoop below the latter, and pivotal connections between the arch and forward end of the scoop; of a hook projecting forward from the rear end of the scoop, a catch

50 supported by the center of the arch and with one side of which said hook engages, a thumb-lever mounted on the main lever, a pawl pivoted within the catch with its tip opposite the free end of the hook, and a rod connecting 55 the thumb-lever with the other end of the pawl, as and for the purpose set forth.

6. In a road-scraper, the combination with the framework, an arch having upright end portions provided with stub-shafts journaled

60 in the framework, laterally-projecting pins at the lower extremities of said end portions, a U-shaped bail pivoted in the framework and having its front ends provided with slots engaging said pins, and guide-fingers rising from said bail; of a scoop pivotally connected

at its forward end with said arch, a lever for moving the latter, and hooks near the rear corners of the scoop engaging the transverse portion of the bail adjacent said guide-fingers thereon, as and for the purpose set forth. 70

7. In a road-scraper, the combination with a framework, an arch having end portions pivotally connected therewith and provided with inwardly-projecting pins at their lower extremities, and a U-shaped bail whose side 75 arms are pivoted within the framework and whose front ends are provided with slots engaging said pins; of a scoop pivotally connected at its forward end with said arch, a lever for moving the latter, and hooks near 80 the rear corners of the scoop engaging the transverse portion of the bail, as and for the purpose set forth.

8. In a road-scraper, the combination with a framework, an arch having upright end portions pivotally connected therewith and provided with inwardly-projecting pins at their lower extremities, and a U-shaped bail whose side arms are pivoted within the framework and whose front ends are provided with slots 90 engaging said pins; of a scoop pivotally connected at its forward end with said arch, a lever for moving the latter, upright guide-fingers on the transverse portion of the bail, and at each rear corner of the scoop a rearwardly-projecting loop engaging one of said guide-fingers and a hook below the loop passing under the bail, as and for the purpose set forth. 95

9. In a road-scraper, the combination with 100 a framework, an arch pivotally supported thereby, a lever for turning the arch, a scoop below the latter, and links pivotally connecting the scoop with the arch; of a bail mounted across the framework in rear of the scoop 105 and having upright guide-fingers, supports projecting rearward from the scoop over the bail adjacent said fingers, a rigid member beneath each support adapted to pass under the bail and shorter in length than its corresponding support, and means substantially as described for moving the scoop bodily to the rear as it is lowered, as and for the purpose set forth. 110

10. In a road-scraper, the combination with 115 a framework, a scoop pivotally supported therein, and means for moving the scoop on its pivots; of an upright transverse guard-plate standing across the mouth of the scoop when the latter is at a carry and having its 120 extremities turned to the rear, and means for adjustably supporting this plate upon the framework, as and for the purpose set forth.

11. In a road-scraper, the combination with a framework, a scoop pivotally supported 125 therein, and means for moving the scoop on its pivots; of an upright transverse guard-plate standing across the mouth of the scoop when the latter is at a carry, rods secured to said plate and passing over the side bars of 130

the framework, their outer ends being slotted, and bolts through said slots and side bars, as and for the purpose set forth.

12. In a road-scraper, the combination with a framework, an arch pivotally mounted therein, and a lever for moving the arch; of a scoop below the arch having hooks at its front corners, links connecting the arch with the scoop, means for supporting the rear end 5 of the latter, and other links carried by the side bars of the framework and engaging those on the scoop when the latter is in a scraping position, as and for the purpose set forth.

13. In a road-scraper, the combination with a framework, an arch having depending ends pivotally mounted therein, cams carried by said ends around such pivots, and a lever for moving the arch; of a scoop below the latter and having hooks at its front corners, pivotal connections between the arch and scoop, means for supporting the rear end of the latter, other hooks pivotally supported by the side bars of the frame and adapted to engage those on the scoop when the latter is lowered, 20 springs pressing these hooks to operative position, and slides moved by said cams to 25

throw these hooks out of engaging position as the scoop is being dumped, as and for the purpose set forth.

14. In a road-scraper, the combination with a framework, longitudinally-slotted blocks rising from opposite side bars and having bearings, a transverse arch having stub-shafts journaled in said bearings, a lever for moving the arch, a scoop below the latter having 30 hooks at its front corners, links pivotally connecting the arch with the scoop, and means for supporting the rear end of the scoop; of L-shaped hooks pivoted at their angles in said framework, slides moving through the 35 slots in said blocks and pivotally connected with the upper arms of the L-shaped hooks, pins in the slides, and cams carried by the arch and engaging such pins, as and for the purpose set forth.

In testimony whereof I have hereunto subscribed my signature on this the 17th day of February, A. D. 1896.

JAMES A. TAYLOR.
